PLLC(57) **CLAIM**

The ornamental design for an aerial vehicle, as shown and described.

DESCRIPTION

FIG. 1 is a perspective view of an aerial vehicle in accordance with the present disclosure;

FIG. 2 is a front view of the aerial vehicle shown in FIG. 1;

FIG. 3 is a back view of the aerial vehicle shown in FIG. 1;

FIG. 4 is a left view of the aerial vehicle shown in FIG. 1;

FIG. 5 is a right view of the aerial vehicle shown in FIG. 1;

FIG. 6 is a top view of the aerial vehicle shown in FIG. 1;

FIG. 7 is a perspective view of the aerial vehicle in an alternative configuration;

FIG. 8 is a front view of the aerial vehicle in the alternative configuration;

FIG. 9 is a back view of the aerial vehicle in the alternative configuration;

FIG. 10 is a left view of the aerial vehicle in the alternative configuration;

FIG. 11 is a right view of the aerial vehicle in the alternative configuration; and,

FIG. 12 is a top view of the aerial vehicle in the alternative configuration.
